J. C. RICHARDSON, OF ILION, NEW YORK.

Letters Patent No. 84,377, dated November 24, 1868.

IMPROVED FORK-BLANK.

The Schedule referred to in these Letters Patent and making part of the same.

To all whom it may concern:

Be it known that I, J. C. RICHARDSON, of Ilion, in the county of Herkimer, and State of New York, have invented a new and useful Improvement in Blank for Spading and other Forks; and I do hereby declare that the following is a full, clear, and exact description thereof, which will enable others skilled in the art to make and use the same, reference being had to the accompanying drawing, forming part of this specification, in which—

Figure 1 represents a bar of metal, with diagrams showing the outlines of the form of the blanks, and

Figure 2 represents a blank, as cut from a bar, and also the finished and a partly finished form in blue and red.

Similar letters of reference indicate like parts.

This invention relates to improvements in the manufacture of spading, manure, or other similar forks, the object of which is to simplify and cheapen the cost of the manufacture.

It consists in punching or cutting the blank out of a plain strip of metal in such a form that no metal is wasted, and which form facilitates the process of finishing the blank, as will be hereinafter described.

I propose to cut from a bar of steel, previously prepared, of suitable width, a blank, A, as shown by the black lines in fig. 2, and in outline in fig. 1, by dies, suitably formed, to give the configuration there shown, and to separate the parts a and b, as represented by the lines c, the said parts a a and b b being the portion of the blank from which the tines are to be formed, and the part d is the portion forming the shank when finished. This part is punched out of the bar, leaving a space, e, which forms the separation between the blank tines a a of the succeeding blank.

The enlarged end of the part d, formed by a corresponding enlargement of the punch, serves to leave the space between the blank tines a a at e of the right form for the finished shape, and saves the labor of spreading

the tines a a, as is done in the present methods of constructing forks, and the curved form given to the shoulders of the blank at f is also retained in the fork when finished, thereby saving a considerable labor in the finishing-operation, and furnishing a much stronger shank than when the latter is cut from the blank at right angles to its finished position, and bent up to the finished form, which often cracks and becomes weakened at the shoulders in bending.

To finish a fork from the blank herein shown, the end tines are turned up at right angles to the shank, and drawn out by rolling or hammering, as shown in red at g, fig. 2. The two central tines, together with the shank, are also drawn out in a similar manner, until they assume the form shown in blue at a' d, fig. 2. After the tines have been reduced to the proper shape, the outer ones are bent down, as represented at b', in the same figure, and the fork completed.

In forming the dies or cutting-apparatus, care is taken to construct them so as to dispose the metal in the right proportion, in the different parts of the blank, to give to each part when finished its due proportion of metal.

The blanks so formed may be finished up, by the present arrangement of forging or rolling-machinery, at less cost than the blanks as usually prepared.

Having thus described my invention,

What I claim as new, and desire to secure by Letters Patent, is—

The blank A, formed by punching or otherwise severing it from a bar of suitable width, with the space e', slits c, and shoulders f, substantially as and for the purpose described.

The above specification of my invention signed by me, this 4th day of August, 1868.

J. C. RICHARDSON.
